Attorney.

UNITED STATES PATENT OFFICE.

DUDLEY R. MORRISON, OF ANDERSON, INDIANA.

HYDROCARBON-ENGINE.

1,382,008.

Specification of Letters Patent. Patented June 21, 1921.

Application filed April 26, 1920. Serial No. 376,677.

To all whom it may concern:

Be it known that I, DUDLEY R. MORRISON, a citizen of the United States, residing at Anderson, in the county of Madison and 5 State of Indiana, have invented new and useful Improvements in Hydrocarbon-Engines, of which the following is a specification.

This invention relates to improvements in 10 hydrocarbon explosive engines for the utilization of kerosene or other fuel oil as a carbon supply, and the object of the invention is,

First, to provide an engine that will start 15 on a light load and which will be self igniting and will continue to operate on a light load.

Second, to provide an oil burning engine 20 in which all of the carbon will be eventually reduced and automatically discharged from the engine without interfering with its continuous and successful operation.

I accomplish the above and other objects 25 which will hereinafter appear, by the mechanism illustrated in the accompanying drawing, in which—

Figure 1, is a longitudinal section on the 30 line 1—1 of Fig. 2 of an engine-cylinder embodying my improvements; and Fig. 2 is a cross section of same on line 2—2 of Fig. 1.

Like characters of reference indicate like parts in the two views of the drawing.

The engine is a two-cycle one having a cylinder 3, a water-jacket 4, exhaust port 5, 35 and air-intake 6. A piston 7 reciprocates in the cylinder and is of usual construction except that it is preferably notched at 8 to more quickly uncover the air intake and to deflect the mixed vapors toward the outer 40 end of the cylinder. This outer end has a special head 9, bolted to the cylinder 3, and packed at the joint at 10.

In the end of head 9, near the lower edge 45 thereof, is a screw-threaded hole in which a tube 11 is screwed. The outer end 12 of this tube is closed while the opposite end is open and discharges into the cylinder. The outside of this bore for the tube preferably has the countersink 13, to expose the 50 maximum outer tube surface to the direct action of an outside heater used in starting the engine. The heater here shown is the well known commercial torch 14, and to concentrate its heat on the tube, I provide 55 a metal hood 15, open at top and bottom and supported from the cylinder-head.

It will preferably be lined with asbestos or other nonconductor 30.

The fuel-oil is supplied through a pipe 16, from a suitable reservoir under pressure 60 of a pump—the reservoir and pump not being shown. This pipe 16 enters the lower portion of the cylindrical extension 17, of the head 9. The hole is countersunk outside at 18 to air-cool the pipe, and the end of 65 the pipe is preferably depressed in a recess 19 to keep the pipe outlet from being clogged with carbon. Only a minimum length of the tube-end is screw-threaded to enter and contact the metal of the head, 70 which is to avoid heating the pipe by conduction from the cylinder. The end of the pipe is closed with the exception of a small discharge hole of approximately the diameter of a number 9 needle. 75

A plate 20 preferably of bronze or other slow oxidizing metal crosses above the pipe 16, from one side of the cylinder-bore to the other, as shown in Fig. 2, and makes a close fit against the vertical end or head 9 80 to which the plate is fastened by ears 21. The inner edge of the plate has a downward flange 22, which conforms to the bore of the cylinder and makes a closure in that direction of the space under the plate. An integral tongue 23, projects into the tube 11 and curves down as shown in Fig. 1, a loose fit of all edges of the tongue being made against tube 11. 85

Secured to the head 9, by a band 34, is 90 a cylindrical drum 25, of bronze, with a closed head at the top, and a head at its lower end with a central opening through which a tube 26 enters the drum and in which the tube is supported. The tube 26 95 is preferably of nickel. It is open at both ends with the upper end terminating within approximately one-fourth inch of the upper head. The lower end of the tube 26 projects about five-eighths of an inch below the bottom of drum 25 and approximately three-sixteenths of an inch above plate 20. 100

The inside diameter of drum 25, is approximately three-fourths of an inch and it is two-and-one-half inches long inside. 105 The inside diameter of tube 26, is approximately one-eighth of an inch.

The operation of my invention is as follows: The engine being cold, to start it the torch 14, is lighted and the oil turned on by 110 opening cock 27. The oil being fed through tube 16 under pressure is forced through

the reduced hole in the end of the tube against the plate 20, and some of the oil will run down the downwardly curved tongue upon the lower wall of pipe 11, 5 where, because the pipe has been heated by the torch, it volatilizes, and, eventually filling the chamber under the plate 20 to overflowing, forces its way out around the edges of the tongue and plate into the cylinder 10 where it mixes with air supplied through intake 6. The resulting mixture coming in contact with the hot pipe 16, is exploded, and the continuance of this operation soon heats the drum 25, and its tube 26, to a permanent temperature that will explode the mixture without the further use of the torch.

At each explosion the flame flashes through the tube into the drum causing a compression in the drum which forces the flame 20 out again into contact with the plate 20, thereby additionally and continuously heating the plate. The resulting temperature of the plate superheats the heavier products of the fuel-oil that have settled at the bottom 25 of the chamber under the plate 20, resolving said products gradually into a red powder, where kerosene is used, which escapes with the vapor into the cylinder from where it is blown out to atmosphere by the action 30 of the engine.

While I have here shown the best form of my invention now known to me it is obvious that many variations in form, size, material, and the like, are possible without departing 35 from the spirit thereof; and I therefore do not desire to be limited any more than is required by the appended claims.

I claim:

1. In a hydrocarbon explosive engine utilizing oil as a source of hydrocarbon supply, 40 a cylinder, a piston reciprocating in the cylinder, a resilient partition within the cylinder defining a separate chamber said plate making a loose fit at its edges with the cylinder, means for supplying fuel-oil to the chamber defined by the plate, and means for heating the plate to vaporize the oil.

2. In a hydrocarbon explosive engine utilizing oil as a source of hydrocarbon supply, 50 a cylinder, a piston reciprocating in the cylinder, a plate-partition within the cylinder defining a separate chamber therein said plate being secured to the cylinder but making a loose fit at its edges with the cylinder to allow it to spring away for the escape of vapors from the chamber, means for supplying fuel oil to the chamber, and means for heating the plate to vaporize the oil and force it out past the edges of the plate.

3. In a hydrocarbon explosion engine utilizing oil as a source of hydrocarbon supply, 55 a cylinder having an outer head, a piston reciprocating in the cylinder, a tubular extension from the cylinder-head closed at its

outer end, a plate-partition within the cylinder fastened to said cylinder-head and defining a chamber separate from the cylinder said plate making a loose fit at its edges with the cylinder and having a tongue entering 70 said tubular extension defining an extension of the chamber, means for initially heating said tubular extension to start the engine, and means to continue heating the plate-partition after the discontinuance of the initial heating. 75

4. In a hydrocarbon explosive engine utilizing oil as a source of hydrocarbon supply, a cylinder, a piston reciprocating therein, a chamber in the cylinder for the initial heating and conversion of the fuel oil into hydrocarbon vapors, and a drum in the cylinder adjacent the chamber having an opening in its part closest to the chamber. 80

5. In a hydrocarbon explosive engine utilizing oil as a source of hydrocarbon supply, 85 a cylinder, a piston reciprocating therein, a chamber in the cylinder for the initial heating and conversion of the fuel oil into hydrocarbon vapors, a drum in the cylinder 90 adjacent the cylinder having an opening in its part closest to the chamber, and a tube open at both ends inserted in the opening of the drum one end of the tube terminating near the upper end of the drum and its other 95 end discharging against said chamber.

6. In a hydrocarbon explosive engine utilizing a fuel-oil, a cylinder, a piston reciprocating therein, a spring partition defining a separate chamber in the cylinder, a fuel-oil 100 supply tube discharging into the chamber through a reduced opening, and means for protecting said opening from stoppages.

7. In a hydrocarbon explosive engine utilizing a fuel-oil, a cylinder, a piston reciprocating therein, a spring partition defining a separate chamber in the cylinder, a fuel-oil supply tube discharging into the chamber 105 through a reduced opening, and means for protecting said opening from stoppages comprising the walls of a recess surrounding 110 the discharge end of said pipe.

8. In a hydrocarbon explosive engine utilizing a fuel-oil, a cylinder having an outer closed end, a piston reciprocating in the cylinder, a tubular extension from the closed end of the cylinder closed at its outer end, a plate-partition within the cylinder defining a separate chamber therein and having a tongue extending into the tubular extension, 115 said tongue being downwardly curved at its outer end, means for supplying fuel oil to the chamber, and means for initially heating the tubular extension.

9. In a hydrocarbon explosive engine, a 125 cylinder, a piston reciprocating therein, an extension head on the outer end of the cylinder having cylindrical sides which extend it beyond the end of the cylinder, a tube closed at its outer end and open at its 130

- inner end passing through and seated in the cylinder head, a fuel-oil pipe discharging through the cylindrical walls of the head, a plate-partition crossing said discharge in a chord of the inner bore of the walls of the extension head said plate-partition having a flange to complete the inner closure of a chamber defined by the plate-partition and also having a tongue entering said tube, and means for initially heating the tube.
10. In a hydrocarbon explosive engine, a cylinder, a piston reciprocating therein, an extension head on the outer end of the cylinder having cylindrical sides which extend the head beyond the end of the cylinder, a tube closed at its outer end and open at its inner end passing through and seated in the cylinder head, a fuel-oil pipe discharging through the cylindrical walls of the head, a plate-partition on a chord of the bore of the head extension having a flange completing the inner closure of the chamber and a tongue entering said tube, a drum above the plate-partition and an open-ended tube in it terminating close to the plate-partition.
